WITNESS:

Patented Dec. 19, 1922.

UNITED STATES PATENT OFFICE.

LEONARD M. THOMPSON, OF DAYTON, WASHINGTON.

STORE FIXTURE.

Application filed May 26, 1922. Serial No. 563,966.

To all whom it may concern:

Be it known that I, LEONARD M. THOMPSON, a citizen of the United States, residing at Dayton, in the county of Columbia and 5 State of Washington, have invented new and useful Improvements in Store Fixtures, of which the following is a specification.

My present invention has reference to a fixture for stores.

10 In carrying out my invention, it is my purpose to produce a store fixture that shall include shelves and bins arranged beneath the shelves, said shelves being arranged at a downward angle and having arranged thereon tracks or ways for canned or packed 15 goods, means being provided for dividing the shelves into compartments for the several classes of goods, and whereby the goods in the several compartments will be effectively displayed and easily removed when purchased.

A further object is to produce a store fixture in which superimposed angularly arranged shelves are disposed above bins, said 25 shelves having arranged thereon rods disposed in spaced pairs and providing therebetween rails or ways for canned or boxed commodities, means being provided for dividing the shelves into separate compartments 30 for the several commodities, said means being adjustable whereby different sized cans or containers may be received therein, the cans or containers gravitating to the outlet for the compartments so that 35 the outermost cans or containers will be constantly displayed and also whereby the same may be readily removed, while the bins are gradually rounded or concaved to outlets at the fronts thereof, the said outlets being 40 normally closed by slidable doors or valves.

The foregoing, and other objects which will present themselves as the nature of the invention is better understood, may be accomplished by a construction, combination 45 and operative association of parts such as is disclosed by the drawings which accompany and which form part of this application.

In the drawings:—

Figure 1 is a perspective view of a store 50 fixture in accordance with this invention.

Figure 2 is a sectional view on the line 2—2 of Figure 1.

Figure 3 is a horizontal sectional view on the line 3—3 of Figure 2.

55 Figure 4 is a horizontal sectional view on the line 4—4 of Figure 1.

Along the sides of walls in a mercantile establishment such as a grocery store, my fixtures are preferably erected, but it will be obvious as the nature of the invention is 60 better understood, that the same may be arranged in the middle or at any other convenient part of a store room.

In the showing of the drawings, I erect along the sides of a wall the vertical or side 65 members 1 of the fixture. The sides, from the outer edge thereof and at a suitable distance from the bottom thereof are widened from their outer edges, the widened portions being indicated by the numeral 2. The 70 widened portions have their outer faces closed by a plate 3 which, in practice, is preferably in the nature of a board or boards, the ledges formed by the projections having secured thereon a plate 4 which forms the 75 top of the bins of the improvement. The lower portion of the fixture may be divided by vertical partitions to provide any desired 80 number of bins, each of the said bins preferably having their inner faces lined with metal, the said metal being concaved downwardly and outwardly, as at 6 whereby the contents of the bins will gravitate to the front 3. The front, at the bottom of the bins proper is provided with outlet openings 7, 85 and preferably the bins are formed with troughs 8 that partly project through the said openings 7. The front, to the sides of the opening, has vertical plates 9 that form 90 ways for slidable doors or valves 10.

The side members 1 are preferably connected together by a cornice 11, and between the side members there may be arranged, if desired, any desired number of vertical partitions.

95 Supported between the sides, and between the partitions when the same are employed, are the shelves 13 respectively. The shelves are disposed in superimposed relation and are arranged each at a downward angle.

100 Adjustably secured to the outer edges of the side members 2 by means 14 at desired distances above the outer edges of the shelves 13, are rods 15. These rods receive the lipped ends 16 of partition plates 17. Binding means 18 pass through the plates 17 and the lips 16 thereof whereby the said partition plates and the lips thereof may be brought into tight frictional engagement with the rods 15. The opposite or inner end 105 of each of the partition plates 17 is extended at a downward angle as at 19, and the said

angle portion is formed with an offset end in the nature of a foot 20, the said foot having an opening therethrough for the reception of a securing element 21 that, of course, 5 enters the shelves. By this arrangement, it will be seen that the partition plates may be suitably spaced to form the shelves with compartments for canned or boxed commodities, and also by the arrangement it will 10 be noted that the outermost can or box will gravitate downwardly on the shelves into contact with the rod 15 whereby the goods will be freely displayed and at the same time readily removable when purchased.

15 To more effectively assure the free sliding movement of the canned or boxed commodities on the shelves in the respective compartments provided between the partitions 17, I 20 secure on the portion of the shelves in each 20 of the compartments a pair of rods 22 respectively. These rods have their ends bent in the same direction, as at 23, the bent portions being inturned, as at 24, the inturned portions being disposed below the respective 25 shelves 13, and securing means such as screws 25 pass through the ends 24 of the rods or rails for adjustably sustaining the same on the shelves.

With my improvement it will be noted 30 that a large number of different classes of canned or boxed goods may be effectively displayed and readily removed from their respective compartments. Thus it is not necessary that a merchant have a separate 35 stand to display such class of commodity, such display usually involving a large number of such commodities, the employment of which would be unnecessary with the employment of my improvement. The bins 40 are, of course, designed to receive therein granular food stuffs, such as flour, rice, etc. The doors or valves may be in the nature of frames having transparent panels so that the commodities in the several bins may be

displayed to the customer as well as to the 45 merchant. The top for the bins is preferably hingedly secured thereto, as at 26, so that the contents of the bins may be replenished when exhausted, and it is thought that the foregoing description when taken in 50 connection with the drawings will fully set forth the construction and advantages of the improvement to those skilled in the art to which such inventions relate.

The bins have a metal lining.

Having described the invention, I claim:—

1. In a store fixture, vertical supports, superimposed downwardly inclined shelves secured therebetween, rods removably and adjustably secured to the supports above the 60 respective shelves, plates having lipped ends surrounding the rods, means binding the lipped ends of the plates on the rods, said plates having inner angle ends which are removably secured to the shelves, said plates 65 dividing the shelves into spaced open compartments, and rails on the shelves in each compartment.

2. In a store fixture, vertically disposed supports, downwardly inclined superimposed shelves arranged between the supports and secured thereto, rods connected to the supports above the shelves, plates adjustably secured to the rods and to the shelves and dividing the shelves into spaced open compartments, spaced pairs of rods removably secured to the shelves in each of the compartments and providing the same with rails, said supports, below the shelves divided into bins, each of said bins having its 75 lower wall dished and extended at an angle toward the front wall thereof, the front wall having an opening in a line with the bottom of each of the bins, and a slidable valve 80 closing said opening.

In testimony whereof I affix my signature.

LEONARD M. THOMPSON.
